CLAIM

The ornamental design of an actuator control unit, as shown and described.

DESCRIPTION

FIG. 1 is a front side perspective view of an actuator control unit, showing my new design;

FIG. 2 is a plan view of a top side thereof;

FIG. 3 is a plan view of a bottom side thereof;

FIG. 4 is a front end view thereof;

FIG. 5 is a rear end view thereof;

FIG. 6 is a bottom perspective view thereof;

FIG. 7 is a left side elevational view thereof; and,

FIG. 8 is a right side end elevational view thereof.
